CLAIM

We claim the ornamental design for a chair, as shown and described.

DESCRIPTION

FIG. 1 is a front perspective view of a chair; FIG. 2 is a front view of a chair of FIG. 1; FIG. 3 is a rear view of a chair of FIG. 1; FIG. 4 is a left side view of a chair of FIG. 1; FIG. 5 is a right side view of a chair of FIG. 1; FIG. 6 is a top view of a chair of FIG. 1; and, FIG. 7 is bottom view of a chair of FIG. 1. The dashed lines are for purposes of illustrating environmental structure and form no part of the claimed design.

1 Claim, 7 Drawing Sheets
